UNITED STATES PATENT OFFICE.

CLARENCE E. SMITH, OF NEW BRITAIN, CONNECTICUT, ASSIGNOR TO
NORTH & JUDD MANUFACTURING COMPANY, OF NEW BRITAIN,
CONNECTICUT, A CORPORATION OF CONNECTICUT.

BUCKLE.

No. 839,817.

Specification of Letters Patent.

Patented Dec. 25, 1906.

Application filed May 16, 1906. Serial No. 317,130.

To all whom it may concern:

Be it known that I, CLARENCE E. SMITH, a citizen of the United States, residing at New Britain, Hartford county, Connecticut, have invented certain new and useful Improvements in Buckles, of which the following is a full, clear, and exact description.

My invention relates to improvements in buckles, and particularly what are known as "sliding-bar" buckles. Heretofore buckles of this character have been somewhat limited in use by reason of the fact that it is exceedingly difficult to release them when under strain.

It is the object of my invention to construct a buckle of this type which may be employed practically for use in a variety of instances—such as trunk-straps, book-straps, skate-straps, and the like—where the buckle and strap are under considerable strain when in use.

The invention consists in improvements preferably as illustrated in the accompanying drawings.

Figure 1 is a perspective view of a strap and buckle of my invention in use. Fig. 2 is a plan view of the buckle detached. Fig. 3 is a longitudinal sectional view of the same.

1 is the strap, in this instance illustrated as applied to a bundle 2, comprised of two books, which are substantially non-yielding in character.

It is intended that the buckle of my invention shall be adapted to application on leather and similar slightly-yielding or non-yielding material. The buckle proper comprises a frame and a slide. The frame is made up of the center bar 3, to which the strap is adapted to be secured, the tuck loop 40 and bar 4, and the presser-bar 5, connected by suitable side bars. The slide 6 is adapted to be moved back and forth along the side bars between the strap-bar and the presser-bar. This slide has an upturned portion or edge 7, having a series of teeth for engaging the strap. The slide also has a shoulder 8. The strap when in use has its end inserted in the opening between the shoulder 8 and the teeth 7. When the strap is pulled taut, the tension on the shoulder 8 moves the slide to

the right, (as viewed in Fig. 3,) so that the teeth 7 are brought into a position to impinge against the under surface of the strap when its end is brought down and tucked under the bar 4. The tension draws the slide to such an extent as to wedge the strap between the presser-bar 5 and the teeth 7. The parts may be readily brought to this position; but unless the article to which the strap is applied or the strap itself is of a yielding character it is difficult to release the strap by a pull on the strap itself, since the tighter the pull on the strap the more securely the teeth hold it. For the purpose, therefore, of making it possible to manually release the slide in a convenient manner I have extended the slide forward beneath the presser-bar 5 and turned the edge up into a lip 9, which is adapted to be readily engaged by the thumb or finger, so as to push the slide away from the presser-bar and release the strap.

While this construction is simple and the improvements may be adapted to buckles of well-known types without much additional expense, it has the advantage of practicality under many conditions to which sliding-bar buckles have previously been ill adapted.

What I claim is—

1. A buckle, comprising a frame having a presser-bar and a tuck-loop, a slide adapted to wedge the strap against a portion of the presser-bar and having a portion adapted to be engaged by a strap for pulling the slide into its wedging position, and having an upturned portion at its forward end for manual engagement and release.

2. A buckle, comprising a frame having a presser-bar and a tuck-loop, a slide adapted to wedge the strap against a portion of the presser-bar and having a portion adapted to be engaged by a strap for pulling the slide into its wedging position, and having an upturned portion at its forward end for manual engagement and release, and a cross-bar with upturned teeth for engaging the strap.

CLARENCE E. SMITH.
